(57) **CLAIM**

We claim the ornamental design for a wireless accessing device, substantially as shown and described.

DESCRIPTION

FIG. 1 is a front, left and top perspective view of a wireless accessing device in accordance with the present design.

FIG. 2 is a rear, right and top perspective view of the wireless accessing device shown in FIG. 1.

FIG. 3 is a front elevation of the wireless accessing device shown in FIG. 1.

FIG. 4 is a right side elevation of the wireless accessing device shown in FIG. 1.

FIG. 5 is a rear elevation of the wireless accessing device shown in FIG. 1.

FIG. 6 is a left side elevation of the wireless accessing device shown in FIG. 1.

FIG. 7 is a top plan view of the wireless accessing device shown in FIG. 1; and,

FIG. 8 is a bottom plan view of the wireless accessing device shown in FIG. 1.

1 Claim, 5 Drawing Sheets
